UNITED STATES PATENT OFFICE

129,949

DESIGN FOR A TOWEL RACK

Roy S. Sanford, Oakville, Conn., assignor to The Autoyre Company, Incorporated, Oakville,
Conn., a corporation of Connecticut

Application August 1, 1941, Serial No. 102,626

Term of patent 14 years

To all whom it may concern:

Be it known that I, Roy S. Sanford, a citizen of the United States, residing at Oakville, in the county of Litchfield and State of Connecticut, have invented a new, original, and ornamental Design for a Towel Rack, of which the following is a specification, reference being had to the accompanying drawing, forming a part thereof.

Fig. 2 is a front elevational view of the towel rack shown in Fig. 1; and

Fig. 3 is a side elevational view of the towel rack shown in Fig. 1.

The characterizing features of my new design reside in the provision of a substantially U-shaped bar disposed with the yoke of said U extending substantially horizontally and with the legs of the U terminating at their respective inner ends in support-engaging brackets and a bar of greater length than said U extending between and secured to intermediate portions of said legs with the free end portions of said second bar extending beyond said legs at each end of said U, all as shown.

I claim:

The ornamental design for a towel rack, substantially as shown and described.

ROY S. SANFORD.
